UNITED STATES PATENT OFFICE

MORLEY PUNSHON REYNOLDS, OF CLEVELAND HEIGHTS, OHIO, ASSIGNOR TO THE
W. S. TYLER COMPANY, OF CLEVELAND, OHIO, A CORPORATION OF OHIO

WOVEN-WIRE SCREEN

Application filed December 27, 1927. Serial No. 242,917.

The present invention, relating as indicated, to a woven wire screen is more particularly directed to a new and improved screen formed of two series of wires woven together to produce a screen having to an unusual degree the quality of free screening and the ability to resist clogging or blinding. A further object of the invention is the provision of a screen having an exceptionally long life and one in which a high degree of vibration can be secured due to the use of highly tempered wires in one series.

To the accomplishment of the foregoing and related ends, said invention, then, consists of the means hereinafter fully described and particularly pointed out in the claims; the annexed drawing and the following description setting forth in detail certain mechanism embodying the invention, such disclosed means constituting, however, but one of various mechanical forms in which the principle of the invention may be used.

In said annexed drawing:—

Fig. 1 is a plan view of my improved screen; Fig. 2 is a section on the line 2—2, Fig. 1; and Fig. 3 is a section on the line 3—3 in Fig. 1.

Referring now to Fig. 1, there is shown a woven wire screen consisting of two series of interwoven wires, of which one series, comprising the wires 1, are disposed in spaced parallel relation, while the other series, comprising the wires 2, are arranged in bands or groups of parallel but closely compacted wires.

The wires 1 may be perfectly straight as illustrated in Figs. 1, 2 and 3, and since these wires are not crimped or bent as in most screens for the engagement of the other series of wires they may be formed of hard drawn wire of a very high degree of flexibility and temper and can thus be made to possess the qualities which will impart to the screen a high degree of vibration in use and a long life due to the hardness of these wires. It will be readily understood that if these wires, after being drawn, had still to be bent and crimped, it would produce an additional temper and hardness

in the wire at the points of bending, which would require the original condition of the wire to be considerably softer than is the case with the wires just described, in order not to produce an excess hardness and brittleness at the bent portions. 55

The transverse wires consist of either square or rectangular wires (in cross-section) which are woven about the parallel spaced round wires of the first series in separated groups. By the use of either square or rectangular wires a very much increased area of engagement between the transverse and longitudinal wires is secured than is possible where round wires are used 60 for both the longitudinal and transverse series. With wires of the cross-sectional area indicated a surface slightly greater in width than the normal width of the wire is engaged at each band on one of the wires 70 of the first series since the transverse wires flatten out slightly when being crimped and woven, and thus increase the normal area of contact, as indicated in Fig. 1, by the bulged lateral portions 4. 65

The series of transverse wires employed in spaced groups may be permanently secured in place by welding or other means at spaced points 5 and 6 on one side of the group and at similar spaced points 7 and 8 on the other, the outermost wires of each group being thus secured to certain of the wires of the other series and thus acting to retain the grouped wires in that relationship and prevent the slipping of any of the wires out of their original and predetermined position. 80

My improved screen has a materially longer life than screens heretofore used for the same purpose by reason of the greater 90 temper and hardness which can be used in the longitudinal wires. It also has a quality of free screening by reason of the large areas in which there are no transverse wires. In addition to these advantages the permanent fixing of the relationship between longitudinal and transverse wires maintains a 95 high degree of accuracy of classification throughout the entire life of the screen.

Other modes of applying the principle 10

of my invention may be employed instead of the one explained, change being made as regards the mechanism herein disclosed, provided the means stated by any of the following claims or the equivalent of such stated means be employed.

I therefore particularly point out and distinctly claim as my invention:—

1. A woven wire screen comprising a series of spaced parallel wires, and a second series of transverse wires, the wires of said second series being arranged in spaced groups, and the two outermost wires in each such group being secured to certain of the wires of the first-named series.
2. A woven wire screen comprising a series of spaced, straight, parallel wires, and a second series of transverse wires, said transverse wires being arranged in spaced groups and being of rectangular cross-section, the two outermost wires in each group being united to certain of the wires of said first-named series.
3. A woven wire screen comprising a series of spaced, straight, parallel wires, and a second series of transverse wires, said transverse wires being arranged in spaced groups and being of square cross-section, the two outermost wires in each group being united to certain of the wires of said first-named series.

Signed by me, this 22nd day of December, 1927.

MORLEY PUNSHON REYNOLDS.
